CHIMNEY CAP

Grover C. Robbins, Blowing Rock, N. C.

Application December 18, 1941, Serial No. 423,423

3 Claims. (Cl. 93—67)

This invention relates to an improved chimney cap and more especially to a structure of this class having means for stimulating the draft in the chimney.

It is a well known fact that ordinary chimneys frequently have insufficient upward draft therein to overcome the down-draft produced by outside currents of air. When a gale of wind blows across the top of a chimney flue there is a tendency for the chimney walls to deflect a portion of this wind downwardly into the flue and thus retard the upward draft. Sometimes the down-draft is sufficient to completely overcome the upward draft, resulting in the chimney draft reversing its direction of travel and filling the house with smoke.

It is an object of this invention to provide a chimney cap so constructed that the outside currents will be directed upwardly when striking the chimney wall, to thereby assume a parallel direction of travel to the up-draft currents in the chimney flue. With this type of construction, the outside air currents will assist rather than obstruct the up-draft in the chimney.

It is another object of this invention to provide a chimney cap which is formed from a pair of flush-top telescopically mounted frustro-pyramidal members, said members having the proximate faces thereof spaced apart to provide a passageway for outside air currents.

It is another object of this invention to provide a chimney cap which is formed from a hollow frustro-pyramidal member supported by the chimney and which acts as a smoke flue, a second frustro-pyramidal member telescopically mounted to form an air passageway, and flat members supported by the top of the chimney for holding the two frustro-pyramidal members in spaced relation to each other.

It is another object of this invention to provide a chimney cap as above described in which the size of the air passageway between the frustro-pyramidal members may be changed to suit the particular chimney upon which the cap is to be placed, and at the same time maintain a flush top relation between the spacer members and the frustro-pyramidal members.

It is still another object of this invention to provide a chimney cap of the class described which can be erected piece by piece very much in the same manner as in brick laying, thereby eliminating the necessity of assembling the entire cap before mounting the same upon the chimney.

Some of the objects of the invention having been stated, other objects will appear as the de-

scription proceeds when taken in connection with the accompanying drawing, in which—

Figure 1 is an isometric view showing my improved chimney cap associated with the top of a chimney;

Figure 2 is a transverse vertical sectional view taken along the line 2—2 in Figure 1;

Figure 3 is an isometric view of the inner flue of my improved chimney cap;

10 Figure 4 is an elevation, showing certain portions thereof in section, illustrating a slightly modified form of chimney cap as it appears when associated with the top of a chimney;

Figure 5 is an isometric view of one of the 15 spacer members associated with the form of chimney cap shown in Figure 4.

Referring more particularly to the drawing, the numeral 10 denotes the upper portion of an ordinary chimney having conventional vertical 20 flues 11 and 12 therein. These flues may or may not be arranged in a symmetrical relation to the chimney; however, in case a flue should be placed in an unsymmetrical relation to the sidewalls of the chimney the present invention is constructed to compensate for this variation.

Disposed on top of the chimney 10 and surrounding the upper end of flues 11 and 12 is a hollow frustro-pyramidal member 14. The inner surface of this member 14 is bell-shaped and 30 when installed upon the chimney it serves to conduct the smoke and gases upwardly from the flues 11 and 12. The outer surface of the member 14 has a plurality of substantially vertically disposed grooves 16 therein into which the inner 35 edges of flat spacer members 18 are adapted to removably fit. Similar grooves 19 are provided at each corner of the frustro-pyramidal member 14. Likewise in each of these grooves 19 a similar flat spacer member 20 is adapted to fit. It

40 will be noted that the spacer members 18 and 20 project downwardly and have lateral flanges or foot portions 21 and 22, respectively, integral therewith. These flange portions rest directly on top of the chimney 10; thereby causing the 45 spacer members to form a tie between the top of the chimney and a second frustro-pyramidal member 24 resting on the upper edges thereof. The members 18 and 20 may be secured to the top of the chimney by any suitable means such 50 as anchor bolts 21a and 22a or if desired a suitable mortar may be employed with equally good results. Particular attention is called to the fact that the upper outer edges of the flat spacer members 18 and 20 are curved in the proper manner to fit the interior walls of the second frustro-

pyramidal member 24; therefore, when the member 24 is placed thereon it will be supported by the upper outer edges of all of the members 18 and 20.

Figure 2 illustrates the relative positions of the inner frustro-pyramidal member 14 and the outer frustro-pyramidal member 24. It is here seen that the spacer members 18 and 20 form an upwardly inclined space between the frustro-pyramidal members into which horizontal currents of wind are adapted to pass. Since the outer surface of the inner member 14 is curved gradually upwardly, the currents of air which enter the space between the frustro-pyramidal members will be directed upwardly in parallel relation to the gases or products of combustion which pass upwardly from flues 11 and 12.

In order to provide a suitable opening for receiving the horizontal currents of wind or air, the lower rim of the outside frustro-pyramidal member 24 is curved to a substantially horizontal position and also to terminate the lower rim at a point above the top of the chimney. The top of the members 14, 18, 20 and 24 are all flush, thereby insuring the currents of air will not mix with the currents from the chimney until the upper extremity of the chimney top has been reached. In this fashion the air currents which usually blow horizontally, will enter between the lower rims of the frustro-pyramidal members 14 and 24 and then be conducted upwardly in parallel relation to the chimney currents to thereby stimulate the draft in the chimney. It is also to be noted that the space between the inner and outer frustro-pyramidal members gradually converges as it progresses upwardly thereby causing the currents of air which enter below the bottom rim of the outer pyramidal member to increase in velocity while moving upwardly.

Figures 4 and 5 show a slightly modified form of the invention in which an improved means is provided whereby the space between the inner and outer pyramidal members may be varied to suit conditions. In this form of the invention, an inner frustro-pyramidal member 30 is provided, said member being adapted to rest on top of the chimney and surround the flues such as designated by reference characters 11 or 12. The member 30 has grooves 31 in its outer periphery into which the inner edges of flat members 32 are adapted to fit, very much in the same manner as in the preceding form of the invention. This flat member 32 likewise has lateral flanges 21 integral with the bottom portion thereof. These flanges are used as a base which rests on top of the chimney. At the corners of the frustro-pyramidal member 30 similar spacer members 33 are provided, each of which has a flanged base 22 for supporting the same on top of the chimney.

The upper outer edges of the spacer members 32 and 33 are used for supporting the inner surface of a second frustro-pyramidal member 38. This member 38 has substantially the same shape as the outer member 24 previously described. In order to place the outer member 38 in proper position relative to the inner member 30 and to provide means for adjusting the relative positions of the inner and outer members, the spacer members 32 and 33 have been cut away as at 39 and 40 thereby leaving posts 41 and 42 respectively. The upper ends of posts 41 and 42 support the lower outer rim of the frustro-pyramidal member 38. The width of each of the upper extremities of the spacer members 32 and

33 is substantially the same as the distance between the inner and outer frustro-pyramidal members. Therefore, the posts 41 and 42 serve as a support for the lower rim whereas the upper outer edges of the members 32 and 33 serve as a support for the upper rim of the member 38. Each of the members 32 and 33 has suitable break lines or grooves 35a, 35b and 35c formed therein on opposed sides of posts 41 and 42. These grooves diminish the thickness of the spacer members to make it more easily broken along desired lines. Similar equally spaced break lines 36a, 36b and 36c are formed in the upper ends of the flat spacer members 32 and 33. The inner frustro-pyramidal member has suitable equally spaced break lines 30a, 30b and 30c formed in its upper portion and at the same distance from the top edge of the cap as the break lines 36a, 36b and 36c. For example, when it is desired to lower the outer-frustro-pyramidal member 38 and thereby decrease the space between the inner and outer members, it is only necessary to break off the posts 41 and 42 along break lines 35a and then break off the upper extremities of the same spacer members along break lines 36a. This will permit the upper frustro-pyramidal member 38 to be lowered a predetermined amount. Then, in order to have all of the members flush top it will be necessary to break off the upper rim of the inner pyramidal member 30 along the break line 30a. If it is desired to lower the outer member 38 still further, the posts 41 and 42 can be broken along break line 35b or 35c and at the same time break off the upper ends of the posts along lines 36b and 36c. Then, in order to make the chimney flue top, a corresponding breaking of the inner member 30 will be necessary along line 30b or 30c.

Particular attention is called to the shape of the outer surfaces of upper cap members 24 and 38 in the two forms of the invention. It will be noted that these exterior surfaces are curved upwardly substantially in parallel with the inner peripheries of these caps. In other words, when the horizontal currents of wind strike these caps, the outer and upwardly disposed peripheries will direct the currents upwardly in parallel with the currents of air which pass between the cap members and thereby serve to prevent the smoke gases which flow upwardly through the inner flues 14 and 30 from being driven downwardly into the chimney.

Another outstanding advantage of my improved chimney cap is its adaptability to chimneys having a plurality of flues which are spaced unsymmetrically of the chimney. As heretofore stated, the entire assembly is adapted to rest on top of the chimney, instead of projecting downwardly on the interior of the chimney flue or on the exterior of the chimney as is the case in many conventional chimney caps. The outwardly flared bottom ends of cap members 14 and 30 permit this cap to surround the upper ends of all of the chimney flues, regardless of the unsymmetrical position. Since the inner cap members do not extend downwardly into the flue, the entire cap assembly may be positioned symmetrically of the chimney and yet serve all of the chimney flues. Of course, the chimney flues may be slightly off-set relative to the vertical center line of the inner cap member, but the flared bottom portion thereof will serve to collect the upwardly flue chimney gases and direct them upwardly. In other words, the ex-

terior appearance of this chimney cap will be entirely symmetrical relative to the chimney regardless of the position of the chimney flues.

In the drawing and specification there has been set forth a preferred embodiment of the invention and although specific terms are employed, they are used in a generic and descriptive sense only and not for purposes of limitation, the scope of the invention being defined in the claims.

I claim:

1. A chimney cap comprising a hollow frustro-pyramidal member adapted to surround the upper end of the chimney flue and to fit on top of the chimney closely adjacent the flue opening, a plurality of spacer members supported by the top surface of the chimney and arranged exteriorly of said member, a second hollow frustro-pyramidal member resting upon said spacers and having its lower rim terminating a substantial distance above the top of the chimney, said second member having its upper rim flush-top with said first member.

2. A chimney cap comprising a hollow frustro-pyramidal member adapted to surround the upper end of the chimney flue and to fit on top of the chimney closely adjacent the flue opening, the outer wall of said member having a plurality of vertically disposed grooves therein, a plurality of flat spacer members supported by the top surface of the chimney and each having one

edge thereof resting in one of said grooves, a second hollow frustro-pyramidal member resting upon said spacers and having its lower rim terminating a substantial distance above the top of the chimney, said second member having its upper rim flush-top with said first member.

3. A chimney cap comprising a pair of flush-top telescopically arranged frustro-pyramidal members, the bottom edge of the outer frustro-pyramidal member being disposed above the bottom edge of the inner frustro-pyramidal member, a plurality of flat spacer members, each having opposed edges thereof abutting the proximate faces of said frustro-pyramidal members, each of said spacer members having a break line at a predetermined distance from the outer edge thereof, each of said spacer members also having a second break line at a predetermined distance from the top edge of said inner frustro-pyramidal member corresponding to the first-named break line, said inner frustro-pyramidal member having a third break line at a predetermined distance from its top rim corresponding to the first and second break lines, whereby the edges of said spacer members can be broken off to allow the outer frustro-pyramidal member to be moved closer to said inner frustro-pyramidal member and whereby the top edge of said inner frustro-pyramidal member can be broken off along a line flush-top with said lower outer member.

GROVER C. ROBBINS.
